UNITED STATES PATENT OFFICE.

HARRY M. SALYER, OF NEW YORK, N. Y., ASSIGNOR TO LUDWIG & COMPANY, OF NEW YORK, N. Y., A FIRM.

PLAYING ATTACHMENT FOR KEY MUSICAL INSTRUMENTS.

SPECIFICATION forming part of Letters Patent No. 734,963, dated July 28, 1903.

Application filed April 17, 1902. Serial No. 103,354. (No model.)

To all whom it may concern:

Be it known that I, HARRY M. SALYER, a citizen of the United States, residing at the city of New York, borough of the Bronx, county 5 and State of New York, have invented certain new and useful Improvements in Playing Attachments for Key Musical Instruments, of which the following is a specification.

The object of my invention is to provide a 10 new and improved playing attachment for key musical instruments which is simple in construction and operation.

In the accompanying drawings, in which like letters of reference indicate like parts in 15 all the figures, Figure 1 is a vertical elevation of my improved playing attachment for musical instruments, parts being broken away and others omitted. Fig. 2 is a vertical transverse sectional view showing the relation between 20 a key, an angle-lever for operating the same, and the bellows-motors for actuating the angle-lever. Fig. 3 is a detail sectional view through an accent-controller. Fig. 4 is an enlarged detail vertical transverse sectional view through a wind-chest, showing 25 the valve mechanisms. Figs. 5 and 6 are enlarged detail sectional views of parts.

The playing attachment is provided with a tracker-bar A, having holes a to register 30 with holes in a suitable music-sheet, (not shown,) which music-sheet during playing is wound from the music-roll B upon a take-up roll C and after playing is rerolled from the said take-up roll C upon the music-roll B. A 35 motor D drives suitable gearing E for rotating the take-up roll C or the music-roll B, and this motor is supported by brackets E' from a partition E², in which the rolls B and C are journaled.

40 B' is a rod for throwing either the roll B or the roll C in gear with the motor, and said rod B' by means of suitable intermediate levers can be shifted from a hand-lever F, suitably pivoted in a convenient position for the 45 manipulator.

The keys b of the instrument are operated by elbow-levers G, pivoted at G' to a suitable rail G², and springs G³ serve for throwing these levers into normal position. That end 50 of each elbow-lever opposite the one acting on the key is connected by suitable rod or

other connecting device G⁴ with the movable board of an exhaust-pneumatic H, of which one is provided for each lever G. Each bellows is attached, by means of its fixed board 55 H', to a tube H², projecting from a valve-casing H³, secured to and projecting from the top of a wind-chest J, and, if desired, the fixed board of the bellows may also be attached to the wind-chest. There are two such 60 wind-chests J, one for the key-striker bellows for the white keys and another for the key-striker bellows for the black keys.

A diaphragm H⁴ is held by a cap H⁵ in the top of the valve-casing H³, and from said cap 65 a tube d extends to a hole a in the tracker-bar. Holes h are provided in the casing H³ directly below the diaphragm. A bore H⁶ is formed in a transverse partition in the valve-casing H³, which bore is in communication 70 with the tube H², leading to a bellows-pneumatic H, and at the end of said bore seats are formed for two valves I' and I² on a stem I³, attached to the diaphragm H⁴ in such a manner that when one valve seats the other 75 is off its seat.

The lower end of the valve-casing H³ fits in a base-ring k, having an internally-threaded neck k', which fits in a hole in the top of the suction wind-chest J. A plug K is inserted 80 into the suction wind-chest J from the bottom and has an externally-threaded neck k³, which is screwed into the neck k' of the ring k until the bottom shoulder k⁴ of the plug K rests against the bottom of the chest. 85

A diaphragm K' is held in the open bottom of the plug K by a cap K², from which two tubes f and f' extend to like caps K² of other plugs K, which other plugs K may be located in the same wind-chest J or in another wind-chest—or, in other words, these tubes f and f' connect two or more caps K² with each other; but one of these caps is always connected by a tube f' with a casing o². A valve-stem K³ rests on the diaphragm K' and carries the valve K⁴, which can seat on an annular shoulder K⁵ in the interior of the plug, and this stem also carries a notched guide-disk K⁶ below the valve K⁴. Ports K⁷ in the walls of the plug K establish communication 90 between the wind-chest J and the interior of the plug. 100

The tracker-bar A, as stated, has a number of holes a and a' , connected with the holes d and o , respectively. The tracker-bar also has a chamber A', connected by a small duct 5 A² with each tube d or o , which ducts can each be adjusted in size by a screw A⁴.

L is a suction-tube connected with the wind-chest, and L' is a branch suction-tube extending to a neck V' in the valve-casing V, which 10 neck can be closed by a valve V², secured to a stem V³, guided in the neck of a cap V⁵, which clamps a diaphragm V⁴ on the casing V, to which diaphragm the valve-stem V³ is attached. A tube V⁶ extends from the cap V⁵ 15 to the tracker-bar A and is connected with the chamber A' in the tracker-bar by a duct A², the same as the other tubes; but this tube V⁶ is closed at the outer surface of the tracker-bar, so that no air can pass from the tracker-bar 20 into said tube V⁶, and it serves only as a suction or exhaust tube. The connecting-tube V⁷ connects the valve-casing V with a valve-casing M, having an interior neck M', forming a seat for a valve M², having a stem M³ 25 attached to a diaphragm M⁴, held on the casing M by a cap M⁵, having a neck which guides the valve-stem M³. A fine vent-aperture m is provided in the diaphragm M⁴. The valve-casing M is connected by a tube 30 L² with a valve-casing N, having an interior neck N', forming a seat for a valve N², attached to a stem N³, secured to a diaphragm N⁴, held by a cap N⁵ on the casing, which valve-stem is guided in the neck of the cap 35 N⁶ and projects through said cap and has a hook N⁶ formed on its outer end. A packing-ring N⁸ reduces the effective area of the diaphragm N⁴. The cap N⁵ has a vent-aperture N⁷. A tube O extends from the valve- 40 casing N to the main chest or suction-chamber, (not shown,) and a tube L³ extends from the neck N' to the wind-chest O' of a series of accent-controllers, of which one is shown in Fig. 3. The same consists of a casing O², 45 communicating at its bottom with the wind-chest O' and having the bore O³ and side channels O⁴ communicating with this bore. A stem O⁵ carries two valves O⁶ and O⁷ for closing the ends of the bore O³, and this stem 50 O⁵ is attached to a diaphragm O⁸, held on the upper end of the casing O² by a cap O⁹, from which a tube o extends to one hole a' of a series of six such holes in one end of the tracker-bar A. The tubes f f', connected with the 55 bottom caps K² of the plugs K, lead to the channels O⁴ and also connect the several plugs K in such a manner that the plugs K of key-striker mechanisms pertaining to the same notes in the several octaves are connected.

A spring P connects the outer end of the valve-stem N³ with the lower end of a pivoted lever P', the lower end of which is also attached to a spring P², fixed at its other end 60 to the frame or the mechanisms.

A tube Q extends from the cap M⁵ of the casing M to a suitable support Q' and can be

closed by a valve Q², attached to a spring Q³, which normally holds this valve off its seat. This spring Q³ is located below the lower end 70 of the lever F and has a cam-shaped end, so that for one position of the lever F the lower end of this lever depresses this spring and holds the valve Q² on its seat, so as to close the end of the tube Q, and in the other position of the lever F the spring Q³ is permitted to rise, so as to open the end of the tube Q. 75

A tube R' extends from the main wind-chest or suction-chamber (not shown) to a valve-casing R, having an interior neck R', 80 forming a seat for a valve R² on a stem R³, secured to a diaphragm R⁴, held on said casing by a cap R⁵, provided with a vent-aperture R⁶ and with a neck guiding the valve-stem R³, through which neck the valve-stem 85 passes. The outer end of the valve-stem R³ is connected by a spring R⁶ and a rod with the lower end of the lever S, pivoted between the levers F and P'. The diaphragm R⁴ rests on a ring S', so that the effective area of the 90 diaphragm is reduced. r' is a suction-tube leading to the motor. As soon as the suction mechanism, which may be of any suitable kind, is operated or suction is produced in any other suitable manner in the main suction-chamber and the lever F thrown into the 95 position shown in Fig. 1 the clutches of the take-up roll C and music-roll B are so shifted that the music-roll is thrown out of gear with the driving mechanism and the take-up roll 100 is thrown in gear with the driving mechanism, so that the music-sheet is unrolled from the music-roll and rolled upon the take-up roll C. By throwing the lever F into the position shown the valve Q² is forced down upon 105 its seat and closes the end of the tube Q, thus preventing the passage of atmospheric air into the cap M⁵. The valve N² is held off its seat by the spring P, thus permitting the air to be drawn through the tubes L² and O from the 110 valve-casing M. Through the small hole m 115 in the diaphragm M⁴ the air is drawn out of the cap M⁵ and the said diaphragm placed in equilibrium—that is to say, the effect of the air-pressure on both sides is the same. The diaphragm M⁴ being in equilibrium and the air-pressure on the left-hand side of the valve 120 M² being less than the pressure on the right-hand side, this valve is lifted off its seat, and thus by means of the tubes L and L' the air 125 is exhausted from the wind-chests J J and from the hollow tracker-bar, which is connected with the neck M' by the tube T. I assume for the present that the plugs K are not provided and that the lower ends of the 130 valve-casings H³ are in direct communication with the wind-chests J. Whenever a hole in the music-sheet (not shown) registers with the corresponding hole a in the tracker-bar, atmospheric air can pass through the corresponding tube d into the cap H⁵ of the corresponding valve-casing H³, and thus the diaphragm H⁴ is placed in equilibrium, as there is atmospheric-air pressure at both sides of

the same. The suction in the chamber J can now draw down the valve I², whereby the valve I² is seated and the bellows H is brought into communication with the wind-chest J and air is exhausted from the bellows, causing the collapsing of the latter, whereby the corresponding elbow-lever G is operated and strikes the key. The parts remain in these positions as long as the hole in the 5 music-sheet registers with the corresponding hole in the tracker-bar. As soon as the music-sheet again closes this hole in the tracker-bar the air is exhausted from the tube d and the cap H⁵, permitting the atmospheric-air pressure acting on the under side of the diaphragm H⁴ to force the latter upward, whereby the valve I² is seated and the communication between the wind-chest and the bellows is interrupted. At the same time the valve 10 I² is unseated, and the bellows can expand under the action of the spring G³ on the elbow-lever G. The same operation is repeated 15 every time a hole in the note-sheet registers with a hole in the tracker-bar.

25 When the accentuation-plugs K are provided, the operation is as follows: The effective area of the upper side of the diaphragm K' is reduced by a ring K¹⁰ so that it is less than the area of the valve K⁴. The atmospheric-air pressure on the under side of the diaphragm K' normally holds the valve K⁴ seated. Whenever the valve I² is unseated, so as to permit the air from the bellows to pass into the wind-chest, the pressure above 30 the valve K⁴ is slightly greater than that below the diaphragm K', because the effective area of the valve K⁴ is somewhat greater than the reduced effective area of the diaphragm K', as before stated, and hence the valve K⁴ is lowered, and the air admitted in the lower part 35 of the casing H³ can pass to the chest J. The valve K⁴ vibrates more or less under the variations of pressure. Whenever a note is to be accentuated, one hole in a series of six 40 rows of holes in the music-sheet registers with a hole a', leading to the accentuation-controller, corresponding to the key-striker mechanism under consideration. Thereby the valve O⁷ of the corresponding accentuation mechanism is unseated in the same 45 manner as described above for the valve I², and thus the tubes f f' of this accentuation-controller are brought in communication with the wind-chest O', and consequently the air 50 is exhausted from those caps K² connected with this controller. The valves K⁴ of the corresponding plugs K are now no longer held on their seat by the atmospheric-air pressure on the lower sides of their diaphragm K', and as the inner area of the diaphragm, which is also subjected to suction, is less in area than the valve K⁴ this valve is held 55 down and unseated by the suction. The air is exhausted from the lower part of the 60 valve-casing H³ and its bellows much more effectively and rapidly, as the exhaust-opening is larger, and thus a more powerful blow 65 is delivered on the key—that is to say, the note is accentuated. When the music-sheet closes the corresponding accentuation-hole 70 in the tracker-bar, the valve O⁷ in the corresponding accentuation-controller is seated, the valve O⁶ unseated, and atmospheric air can pass through the tubes f f' to the several caps K² and the valve K⁴ is again seated 75 by atmospheric air-pressure. The valve K⁴ is opened only for an instant when the accentuation is not used; but when the accentuation comes into power it is held clear off its seat. A note can be struck without accentuation as often as may be desired and when desired may be accentuated, all that is necessary being to provide a proper accentuation-hole in the music-sheet, so that this accentuation-hole will register with the tracker-bar at precisely the same time that the ordinary playing-hole in the sheet pertaining to the note-striker mechanism to be operated registers with the tracker-bar. The normal position of the valve I² is off its seat on account of its weight, and immediately as the instrument begins to play it is essential to have these valves seated, and for this purpose air should be exhausted from the tracker-chamber A', which causes the unseating of 80 the valve M² and the immediate seating of the valve V², thus preventing the air from being drawn out of the wind-chest for the time being; but it permits of withdrawing the air from the chamber A' in the tracker-bar by means of the tube T. The result is that the air is exhausted from all the tubes d and caps H⁵ and the valves I² are seated. At the same time the air is withdrawn by means of the tube V⁶ from the cap V⁵ and the diaphragm V⁴ in the casing V is placed in equilibrium, and the suction on the top of the valve V² can now lift this off its seat and then the air can be withdrawn from the wind-chests J through the tubes L in the 85 manner described, and this continues as long as the instrument operates. When the lever P' is in the position shown in Fig. 1, the spring P has its greatest tension, and this holds the valve N² open to its greatest extent and the instrument plays loudest. When softer playing is desired, the upper end of the lever P' is moved to the left, whereby the spring P is slackened, permitting the valve N² to approach its seat to a greater extent. By manipulating this lever the player is thus enabled to play loud or soft, as he may desire. The spring R⁶ is normally of such strength 90 that when the lever S is in the position shown the instrument plays at normal speed. When the upper end of the lever S is moved farther to the right, the tension of the spring R⁶ is decreased and the valve R² brought nearer its seat, and, vice versa, when the upper end of the lever S is moved to the left 95 the tension of this spring is increased and the valve R² is held farther from its seat, and thus the speed of the instrument is increased. The operator can thus readily control the 100 105 110 115 120 125 130 135

speed by moving the lever S. The suction on the left-hand end of the diaphragm R⁴ tends to seat the valve R², and the tension of the spring R⁶ tends to unseat it. If on account of operating the suction-bellows more rapidly the suction is increased, this greater suction also acts on the diaphragm R⁴, and thus brings the valve R² nearer its seat, and as the suction in the main wind-chest decreases the suction on the left-hand end of the diaphragm R⁴ decreases correspondingly, and thus the pull against the spring R⁶ is less. The valve R² is thus automatically held in proper relation to its seat, according to the tension on the spring R⁶, or, in other words, it is self-governing.

r' is a suction-tube leading to the motor.

Having described my invention, what I claim as new, and desire to secure by Letters Patent, is—

1. In a playing attachment for mechanical musical instruments, the combination with a suction wind-chest, of a valve-casing, a base fitted to the valve-casing, a plug passed through the wind-chest and secured to said base, and an accentuating-valve in said plug, substantially as set forth.

2. In a playing attachment for mechanical musical instruments, the combination with a suction wind-chest, of a base-ring set into the same and having an internally-threaded neck, a valve-casing fitting said base, a valve in said valve-casing, a pneumatic connected with the valve-casing, a plug passed through the wind-chest from the bottom, and having an externally-threaded neck which is screwed into the internal neck of the base-ring, substantially as set forth.

3. In a playing attachment for mechanical musical instruments, the combination with a suction wind-chest, of a valve-casing on the same, a valve in said casing, a pneumatic connected with the casing, a plug in said casing and having apertures establishing communication between the chest and the interior of the plug, a valve in said plug, and diaphragm acting on said valve, substantially as set forth.

4. In a playing attachment for mechanical musical instruments, the combination with a suction wind-chest, of a valve-casing on the same, a valve in said casing, a pneumatic connected with the casing, a plug passed through the wind-chest and in communication with the valve-casing, which plug is provided with apertures communicating with the wind-chest, a valve located in said plug above the apertures, a diaphragm for actuating the valve in the plug, the area of which diaphragm is less than that of the valve, substantially as set forth.

5. In a playing attachment for mechanical musical instruments, the combination with a valve-casing for controlling the passage of air, of a valve in the same, a spring connected with said valve, a pneumatic device for seat-

ing said valve, and an actuating device connected with said spring, substantially as set forth.

6. In a playing attachment for mechanical musical instruments, the combination with a valve-casing, of a valve in the same for controlling the passage of air, a diaphragm for holding said valve on its seat, a spring connected with said valve for holding it off its seat, and means outside of the casing for adjusting the tension of said spring, substantially as set forth.

7. In a playing attachment for mechanical musical instruments, the combination with a valve-casing, of a valve in the same for controlling the passage of air, a diaphragm for holding said valve on its seat, a spring connected with said valve for holding it off its seat, a pivoted lever connected with said spring, substantially as set forth.

8. In a playing attachment for mechanical musical instruments, the combination with a casing having an internal neck, a tube communicating with the casing, another tube communicating with the neck, a valve fitting on said neck, a stem on said valve, a diaphragm held on the casing and connected with said stem, a cap on the casing and forming a guide for the stem, a spring connected with said stem and means for changing the tension of said spring, substantially as set forth.

9. In a playing attachment for mechanical musical instruments, the combination with a motor, of a music-roll and a take-up roll, of means for throwing either of these rolls into gear with the motor, a lever for operating such means, a valve-casing, a valve in the same, a diaphragm on the casing to which diaphragm the valve is secured, a cap over said diaphragm, means for producing suction in the casing, a tube extending from said cap, a valve for closing the end of said tube and means for operating said valve from the lever that is used for operating the motor-gear, substantially as set forth.

10. In a playing attachment for mechanical musical instruments, the combination with a motor and a music-sheet rolling and rerolling gear, a lever for shifting the motor music-roll gear, a valve-casing, a valve in the same, a diaphragm in the casing, to which diaphragm the valve is secured, a cap over said diaphragm, means for producing suction in the casing, a tube extending from said cap, a valve for closing the end of said tube, which valve is operated from the lever that is used for shifting the music-roll gear, substantially as set forth.

11. In a playing attachment for mechanical musical instruments, the combination with a suction-tube, of a motor connected therewith, a valve-casing interposed in said suction-tube, a valve in said casing, means for seating the valve by suction and a lever for unseating the valve, substantially as set forth.

12. In a playing attachment for mechanical musical instruments, the combination with suction wind-chests, and key-striker mechanisms connected with said chests, of a tube 5 for exhausting air from said chests, a tracker-bar having a chamber, two valve-casings interposed in said tube, a valve in each casing, a diaphragm in each casing connected with the valve, a cap over each diaphragm, a tube 10 extending from the cap of the valve nearest the suction wind-chest to the chamber in the tracker-bar, a tube extending from the chamber in the tracker-bar to a point in the said tube between the two valves, substantially as 15 set forth.
13. In a playing attachment for mechanical musical instruments, the combination with suction wind-chests and key-striker mechanisms connected with said chests, of a tube for 20 exhausting air from said chests, a tracker-bar having a chamber, two valve-casings interposed in said tube, a valve in each casing, a diaphragm in each casing connected with the corresponding valve, a cap over each dia- 25 phragm, a tube extending from the cap of the valve-casing nearest the suction wind-chest to the chamber in the tracker-bar, a tube extending from the chamber in the tracker-bar to the said suction-tube at a point between the 30 two valves, a diaphragm of the second valve from the wind-chest having an equalizing aperture and means connected with the cap of this second valve for admitting or exclud-

ing atmospheric air at will, substantially as set forth. 35

14. In a playing attachment for mechanical musical instruments, the combination with suction wind-chests and key-striker mechanisms connected with the same, of a tube for exhausting the air from said chests, a tracker-bar having a chamber, a tube for exhausting the air from said chamber in the tracker-bar, and means for first exhausting the air from the chamber in the tracker-bar, and then from the wind-chests, substantially as set forth. 40 45

15. In a playing attachment for mechanical musical instruments, the combination with suction wind-chests, and key-striker mechanisms connected with the same, of a tube for exhausting the air from said chests, a 50 tracker-bar having a chamber, a tube for exhausting the air from said chamber in the tracker-bar, a valve mechanism for controlling the exhausting of air from the wind-chests, and means for automatically opening 55 said valve by exhausting the air from the chamber in the tracker-bar, substantially as set forth.

In testimony whereof I have signed my name to this specification, in the presence of 60 two subscribing witnesses, this 10th day of April, 1902.

HARRY M. SALYER.
